UNITED STATES PATENT OFFICE

CLESSON E. MASON AND ARNOLD M. DIXON, OF FOXBORO, MASSACHUSETTS, ASSIGNEES
TO THE FOXBORO COMPANY, OF FOXBORO, MASSACHUSETTS, A CORPORATION OF
MASSACHUSETTS

CONTROLLER

Application filed September 15, 1930. Serial No. 482,126.

This invention relates to controlling the flow of fluid to a locus to establish and maintain at a predetermined value a variable condition at the locus. The particular object is 5 to provide cooperating means for effecting a major flow of fluid by means of which the variable condition may be brought approximately to the desired value, either initially or in the event of a major fluctuation, and 10 a minor flow closely to control conditions.

An application of our invention is the control by means of suitable thermostatic controls of the flow of steam to a chamber to be heated thereby and by way of definiteness we 15 shall in the following description of an example of our invention refer to such an application. The illustrative embodiment of our invention referred to will be well understood by reference to the following description 20 thereof taken in connection with the accompanying drawing, wherein:—

Fig. 1 is a partly diagrammatic view of an installation with parts in section; and

Fig. 2 is an enlarged section through the 25 valve which controls the flow of fluid.

In the exemplary embodiment of our invention shown in the drawing the flow of steam to chamber 3 is controlled by a single valve 5 in the steam pipe 7. The valve, however, is provided with ports such that it may 30 function as a valve of large opening to provide a major flow of steam and a valve of relatively small opening to provide a minor flow. Herein the valve proper (see Fig. 2) has a 35 body in the form of a vertically reciprocating hollow piston 9 which is provided with graduated ports having a minor port portion 11, herein shown as triangular in form, with a major port portion 13, herein rectangular in 40 form and of markedly increased base so that at least one side of the combined opening exhibits a marked step or break as shown in the figure. Supposing the valve to lift from the position shown in Fig. 2, a gradually 45 increasing flow initially takes place as the triangle 11 passes the wall 15. Then as the upper boundary of the port portions 13 passes this point a suddenly increased flow is initiated.

50 The valve may be operated by means of

a suitable motor 17, herein shown as a well known type of diaphragm motor. For opening the valve high pressure fluid may be supplied to the motor from supply pipe 19 through a control head H. P. The control head embodies a suitable valve 21 for alternatively opening and closing the communication between the source of pressure fluid at 19 and the motor 17, the valve being supported on a hollow stem 23 which is carried by the expandable diaphragms 25 having a bleeding or exhaust port in the adjustable nozzle 27 controlled by a valve 29 operated by a suitable thermometrically responsive device 31 connected with the thermometer bulb 33 in chamber 3. The construction of the control couple 27—29 may be substantially as shown in the patent to Dixon 1,582,868, April 27, 1926, and need not be more fully 70 described herein.

With the parts in the position shown, pressure fluid flows freely through the head H. P. to motor 17 and the valve is opened wide. Fluid is also escaping through the hollow valve stem 21 and through bleeding port 27 and the diaphragms 25 are collapsed as they are vented to the atmosphere. The chamber rapidly heats up due to the great flow of fluid through the port portions 13 of valve 5. As 80 the temperature approaches the desired control point and at a predetermined interval therefrom, valve 29 closes, pressure builds up in diaphragms 25 and valve 23 moves to the right, shutting off further supply of fluid from pipe 19. The construction of the valve, however, as seen from the figure, is such that no exhaust passage is open to the atmosphere as is customary in devices of this kind. The valve 21, in other words, is a simple valve, 85 merely opening or interrupting communication between two points.

Control of the valve 5 is then taken over by cooperating mechanism which controls the flow of fluid at a relatively low pressure, 95 for instance, from pipe 19 through a reducing valve 35 or similar means for restricting the free flow of fluid, through pipe 37 and control head L. P. to the motor 17. The control head L. P. embodies a supply and waste 100 valve 39 carried by a hollow stem 41 mounted

on diaphragms 43 which are in communication with a bleeding port in nozzle 45 with which cooperates the valve 47. In the example of the invention shown the valve 47 5 serves to throttle more or less the exhaust or bleeding port in nozzle 45 and the construction may be as shown in the patent to Bristol 1,641,944, September 6, 1927, and need not herein be more fully described.

10 With the valve 29 closed and the flow of fluid through the control head H. P. interrupted as described, the motor operates under a relatively reduced pressure, the high pressure existing in the motor being equalized by exhaust through hollow stem 41 of the valve 39 and exhaust port in nozzle 45, the reduced pressure in motor 17 permits valve 5 partially to close and the triangular portion 11 of the port functions. With the valve 47 15 open fluid at relatively low pressure flows to the motor 17 and in part bleeds through the control couple 45-47. As, however, the temperature approaches the desired point, valve 47 throttles more or less the control 20 point permitting pressure to build up in the diaphragms 43. Valve 39 is shifted more or less to the left, throttling the flow of fluid to the motor 17 and permitting partial exhaust of the motor through the partly opened 25 waste port 51 at the left of the valve 39 and permitting the main valve 9 to move toward the closed position. Finally, if the valve 47 is completely closed, the flow of fluid to the motor is completely stopped, the motor is 30 exhausted to atmosphere and the valve completely closed.

35 We are aware that the invention may be embodied in other specific forms without departing from the spirit or essential attributes 40 thereof, and we therefore desire the present embodiment to be considered in all respects as illustrative and not restrictive; reference being had to the appended claims rather than to the foregoing description to indicate the 45 scope of the invention.

We claim:

1. Means for controlling the flow of fluid to a locus thereby to affect the value of a variable condition at the locus comprising, in 50 combination with means responsive to the variable condition at the locus, a valve having ports of marked different area, a motor for moving the valve successively to bring into action said ports and control couples 55 governed by said responsive means to supply pressure fluid at respectively different pressures to said motor.
2. Means for controlling the flow of fluid to a locus thereby to affect the value of a 60 variable condition at the locus comprising, in combination with means responsive to the variable condition at the locus, a valve having a port at least one side of which defines a marked step, a motor for moving the valve 65 successively to render effective the portions

at opposite sides of said step, and control couples governed by said responsive means to supply pressure fluid at respectively different pressures to said motor.

3. Means for controlling the flow of fluid 70 to a locus thereby to affect the value of a variable condition at the locus comprising a valve having a graduated port, a motor for operating the valve, control mechanism for supplying respectively operating fluid at 75 relatively high and low pressures to the motor and control couples governing the same and means responsive to the fluctuations of the variable at the locus for operating the couples.

4. Means for controlling the flow of fluid to a locus thereby to affect the value of a variable condition at the locus comprising valve means having relatively large and small ports, motor means for actuating the valve means, a control mechanism for supplying pressure fluid to the motor means to bring into action the large port, a control mechanism for supplying pressure fluid to the motor means to bring into action the small port, and control couples governing said mechanisms operating respectively at different values of the variable condition at the locus.

5. Means for controlling a flow of fluid 95 to a locus whereby to maintain at a predetermined value a variable condition at the locus, comprising valve means having large and small ports, means effective when the variable has a value determinately different from said predetermined value for operating said valve means to work the large port, and cooperating means effective when the variable is substantially of such predetermined value for operating said valve means to work the small port.

6. Means for controlling a flow of fluid to a locus whereby to maintain at a predetermined value a variable condition at the locus, comprising valve means having large and small ports, means effective when the variable has a value determinately different from said predetermined value for operating said valve means to open or shut the large port, and cooperating means effective when the variable more closely approaches such predetermined value to operate said valve means to work said small port with a throttling action.

7. In combination with a pressure operated motor, means for supplying fluid thereto comprising a simple valve for opening or closing communication of said motor with a source of fluid at relatively high pressure, a supply and waste valve for admitting to or exhausting from said motor fluid at relatively low pressure, means for moving said valves subject to the several pressures, bleeding ports for said means, valves for said ports and means responsive to the fluctuations of a

variable which is affected by the operation of said motor, said means effective to close the last mentioned valves at different values thereof.

5 8. In combination with a pressure operated motor, means for supplying fluid thereto comprising a simple valve for opening or closing communication of said motor with a source of fluid at relatively high pressure, a 10 supply and waste valve for admitting to or exhausting from said motor fluid at relatively low pressure, means for moving said valves subject to the several pressures, bleeding ports for said means, a valve responsive to 15 the fluctuations of a variable which is affected by the operation of said motor, said valve arranged to close the bleeding port pertaining to the high pressure system at a predetermined value of the variable, and a valve responsive to the fluctuations of the variable arranged to throttle the port pertaining to the low pressure system as a second determinately different value is approached.

9. Means for controlling the flow of fluid 25 to a locus to establish and maintain at a predetermined value a variable condition at the locus comprising a valve for the fluid, motor means for moving the valve, and cooperating controllers responsive to the fluctuations of 30 the variable for governing said motor, the one going out of action when said variable determinately differs from said predetermined value and then determining a certain opening of said valve and the other governing 35 the motor between said position and closed position of the valve as the variable approaches said predetermined value.

10. Means for controlling the flow of fluid to a locus thereby to affect the value of a 40 variable condition at the locus comprising a valve, a motor for moving the same, means to supply pressure fluid to the motor at relatively high and low pressures to open the valve to greater or less degree comprising 45 high and low pressure control mechanisms and control couples governing said mechanisms and operating respectively at different values of the variable at the locus.

11. Means for controlling the flow of fluid 50 to a locus to establish and maintain at a predetermined value a variable condition and the locus comprising valve means having ports of large capacity and small capacity, motor means for operating the valve means, 55 and control mechanisms for energizing the motor means comprising elements responsive to the fluctuations of the variable, one effective when said variable reaches a value determinately different from said predetermined 60 value to energize the motor means to close the port of large capacity and the other effective as said variable approaches the predetermined value to energize the motor means to close the port of small capacity.

65 12. Means as described in claim 11 where-

in the port of small capacity is a graduated one.

13. Means as described in claim 11 wherein the ports are organized in a single valve to provide an abrupt change in flow as the 70 valve travels to open successively the small and large ports.

14. Means for controlling a flow of fluid to a locus whereby to establish and maintain at a predetermined value a variable condition at the locus comprising valve means having large and small ports, motor means for opening the same, a source of pressure fluid for operating the motor means, valve mechanism to control the flow of fluid to the motor means, pressure operated means for shifting the same, a pair of bleeding ports for said pressure operated means, means between the ports restricting free flow of fluid through one as compared with the other, a valve for said other port responsive to close the same when the variable reaches a value determinately different from said predetermined value whereby to change pressure conditions 80 in the system and a valve for said one port responsive to close the same as the variable approaches said predetermined value.

15. In combination with a pressure operated motor, a source of pressure fluid for operating the same, valve mechanism to control the flow of fluid to the motor, pressure operated means for shifting the same, a pair of bleeding ports for said pressure operated means, means between the ports for restricting free flow of fluid through one as compared with the other, and valve means adapted successively to close first said other port whereby to change pressure conditions in 95 the system and thereafter said one port.

In testimony whereof, we have signed our 105 names to this specification.
